BOTTOM RING FOR HOT TOPS AND MOUNTING MEANS THEREFOR

Walter M. Charman, Shaker Heights, Ohio

Application April 1, 1949, Serial No. 35,015

5 Claims. (Cl. 22—147)

1

This invention relates to improvements in bottom rings and mounting means therefor. The invention has to do with composite hot tops, that is hot tops comprising metal casings and refractory linings therefor, by means of which a pool of molten metal is maintained above the ingot mold for filling the pipe cavity which forms as the metal in the mold cools. A hot top of this character is disclosed in the prior art, for example in my previous Patent 2,258,483 dated October 7, 1941.

In order to protect the lower end of the casing the hot top of the prior art includes a bottom ring of refractory material temporarily supported upon the metal casing, which ring is intended for a single use and remains behind on the ingot when the hot top is stripped therefrom. Such a ring is conventionally formed with an inner rim which extends above the general upper surface of the ring and by engagement with the ledge prevents lateral movement of the ring such as tends to occur occasionally when the ring strikes the mold as the hot top is being lowered thereinto.

It has long been appreciated that bottom rings with tapered inner walls would be desirable since such a ring would form a beveled shoulder on the ingot. Heretofore it has not been practical however to make bottom rings with tapered inner surfaces because of prohibitive costs in the molding of such rings.

An object of the present invention therefore is the provision of a bottom ring with a tapered inner surface which may be produced readily and economically by ordinary molding operations.

Another object is the provision of means for preventing lateral dislocation of such a ring relative to the hot top casing.

Other objects and features of novelty will appear as I proceed with the description of that embodiment of the invention which, for the purposes of the present application, I have illustrated in the accompanying drawing, in which

Fig. 1 is an elevational view on a small scale of an ingot formed in a big end up mold provided with a composite hot top having a tapered bottom ring in accordance with my invention.

Fig. 2 is a bottom plan view of my improved hot top, a portion of the bottom ring being broken away.

Fig. 3 is a fragmental sectional view taken substantially on the line 3—3 of Fig. 2 but on a larger scale.

Fig. 4 is a fragmental elevational view, partly in section, of an inverted hot top like that of Figs. 2 and 3.

2

Fig. 5 is a fragmental bottom plan view of a modification.

Fig. 6 is a fragmental elevational view of the same, and

Fig. 7 is a fragmental vertical sectional view showing a prior art construction.

In the drawing the metal casing of a composite hot top is shown at 10. It has an inwardly extending bottom ledge 11 upon which are supported semipermanent refractory lining blocks 12. 13 is a refractory bottom ring, which is a molded product. It has a generally flat upper surface 14 and an upwardly and inwardly inclined inner surface 15, by reason of which the ring is sometimes referred to as a tapered bottom ring. It is supported from the casing 10 by means of spring wire clips 16 which engage the lower outer edge of the ring and have inturned upper ends which are adapted to be snapped into sockets 17 formed in the casing wall.

The lower surface of ledge 11 is generally flat, as indicated at 18. At opposed points it is provided with downwardly extending projections or pads 19. These pads may be of the order of one-half inch or less in thickness. In the smaller sizes of hot tops two such pads are sufficient. A larger number may be desirable for larger size hot tops. They may be positioned at opposed corners of the ledge or at points other than the corners if desired. The bottom ring is formed with indentations 20 to receive the pads 19. In the molding of the bottom ring the flat upper surface 14 is the strike-off surface. The indentations may be formed by placing loose pieces in the mold beneath the strike-off surface, by cutting the green ring while still soft, or by grinding or cutting the hard finished refractory. It is not necessary that there be a close fit between the pads and the indentations, for the clearances can be filled with slurry when the ring is mounted upon the inverted hot top. A sheet metal wiper-strip 9 of conventional form may be interposed between ring 13 and bottom ledge 11.

Figs. 5 and 6 show a pad 21 of slightly different form which may be employed at each of the corners of a rectangular hot top or at three or more evenly spaced points of a circular hot top.

When the bottom ring 13 has been placed upon the inverted casing 10 and the clips 16 put in position to attach the ring to the casing the operator trowels a heat resistant slurry or grout 22 into the annular space between the overhanging edge of the lining 12 and the upper surface of the ring 13 to fill and seal this joint and provide a smooth inner surface between the upper

lining and the bottom ring. Thereafter the hot top is subjected to a drying temperature to expel moisture from the grout and harden it.

In Fig. 7 I have illustrated a conventional bottom ring construction of the prior art, 23 being the bottom ledge of a metal casing, 24 being the semipermanent lining resting upon the ledge and 25 being the bottom ring. When such a ring is molded the bottom surface 26 is the strike-off surface. 27 is the upwardly projecting rim on the bottom ring which approximately meets the lower edge of the upper lining, any clearance being taken up with slurry or high temperature cement. In the majority of cases the handling of the hot top does not tend to loosen the bottom ring, but frequently mishandling occurs, causing the hot top assembly as it is being set into the mold to swing against the mold wall as the crane man and his helpers lower it into operating position. The swinging hot top because of its mass possesses considerable energy and if it is arrested by the ring striking the mold a tendency to displace the ring relative to the hot top casing is experienced. The rim 27 of the Fig. 7 construction in connection with the cement or grout behind it prevents any dislocation of the ring under such circumstances.

The ring 13 of the present invention, having a flat upper surface, would slide laterally across the flat lower surface of the ledge if it were not for the pads 19 or 21. These pads in cooperation with the indentations in the bottom ring effectively prevent such accidental lateral dislocation of the ring.

Having thus described my invention, I claim:

1. In a composite hot top, a metal casing having a generally flat lower surface, a plurality of spaced projections depending from said flat surface, a refractory heat insulating bottom ring with a generally flat upper surface engaging the lower surface of said casing and an upwardly tapered inner surface, and provided with indentations to receive said depending projections, and means for supporting said bottom ring from said casing.

2. In a composite hot top, a refractory metal casing having an inturned bottom ledge for supporting a semipermanent refractory heat insulating lining, said ledge having a generally flat lower surface, projections extending downwardly from said flat surface at two opposed corners of said ledge, a refractory heat insulating bottom ring with a generally flat upper surface engaging the flat lower surface of said ledge and an upwardly tapered inner surface, and provided with

55

indentations to receive said depending projections, and means for supporting said bottom ring from said casing.

3. In a composite hot top having a metal casing with an inturned bottom ledge and a semipermanent refractory heat insulating lining supported by and overhanging said ledge, said ledge having a generally flat lower surface, projections extending downwardly from said flat surface at opposed points of said ledge, a refractory heat insulating bottom ring with a generally flat upper surface engaging the flat lower surface of said ledge and an upwardly tapered inner surface and provided with indentations to receive said depending projections, means for supporting said bottom ring from said casing, and a dried grout ring seal filling the space between the overhanging portion of said semipermanent lining and said bottom ring.
- 10 4. A molded refractory heat insulating bottom ring for use upon a hot top casing, said ring having an upwardly and inwardly inclined inner surface and a generally flat upper surface, the latter surface being provided with a plurality of spaced indentations adapted to receive casing projections for holding the ring against lateral displacement.
- 15 5. In a composite hot top, a metal casing having an inturned bottom ledge for supporting a semipermanent refractory heat insulating lining, said ledge having a generally flat lower surface, projections extending downwardly from said flat surface, a refractory heat insulating bottom ring with a generally flat upper surface engaging the flat lower surface of said ledge and an upwardly tapered inner surface, and provided with indentations to receive said depending projections, and means for supporting said bottom ring from said casing.
- 20 6. In a composite hot top, a metal casing having an inturned bottom ledge for supporting a semipermanent refractory heat insulating lining, said ledge having a generally flat lower surface, projections extending downwardly from said flat surface, a refractory heat insulating bottom ring with a generally flat upper surface engaging the flat lower surface of said ledge and an upwardly tapered inner surface, and provided with indentations to receive said depending projections, and means for supporting said bottom ring from said casing.
- 25 7. In a composite hot top, a metal casing having an inturned bottom ledge for supporting a semipermanent refractory heat insulating lining, said ledge having a generally flat lower surface, projections extending downwardly from said flat surface, a refractory heat insulating bottom ring with a generally flat upper surface engaging the flat lower surface of said ledge and an upwardly tapered inner surface, and provided with indentations to receive said depending projections, and means for supporting said bottom ring from said casing.
